R. T. HARTNETT,
ASH REMOVER.
APPLICATION FILED MAR. 8, 1920.

1,365,781.

Patented Jan. 18, 1921.

UNITED STATES PATENT OFFICE.

RAYMOND T. HARTNETT, OF PORT CARBON, PENNSYLVANIA.

ASH-REMOVER.

1,365,781.

Specification of Letters Patent. Patented Jan. 18, 1921.

Application filed March 8, 1920. Serial No. 364,008.

To all whom it may concern:

Be it known that I, RAYMOND T. HARTNETT, a citizen of the United States, residing at Port Carbon, in the county of Schuylkill and State of Pennsylvania, have invented new and useful Improvements in Ash-Removers, of which the following is a specification.

This invention relates to ash removing devices for the removal of ashes and so forth from the ash-pits of stoves, heaters, ranges and furnaces, and it has for its main object to provide a device which may readily be applied to any kind or type of ash-pit or ash receiving chamber either in its original installation or at any desired time thereafter.

Another object of this invention is to provide a device of the character referred to which will effectively remove all ashes and cinders without liberating any portion thereof into the cellar or other part of the house or surroundings to cause undesirable dust and dirt.

Still further the invention has for an object to provide a device of the nature referred to which is simple in construction, cheap to manufacture, and easy to install; and one which when in use is exceedingly effective and cleanly for the purpose specified.

With the foregoing main objects in view my invention consists essentially in the novel features of construction, combination and arrangements of parts hereinafter fully described and more particularly defined by the appended claims.

In the further disclosure of the invention reference is to be had to the accompanying sheet of explanatory drawings constituting a part of this specification and in which like characters of reference designate the same or similar parts in all the views.

Figure 1— is a broken fragmentary sectional elevation of part of a kitchen stove and ash box showing one form of my invention applied thereto.

Fig. 2— is a transverse vertical section through the ash-remover proper taken substantially on the line 2—2 in Fig. 1— and looking in the direction of the arrows.

Fig. 3— is a similar vertical section taken on the line 3—3 in Fig. 1 and looking toward the right hand thereof.

Fig. 4— is a face view of the ash-box door 55 illustrating my improved ash-remover in position; and,

Fig. 5— is a fragmentary elevation of a slightly modified form of the invention parts being broken away or in section for 60 the sake of clearness.

Referring more particularly to Figs. 1 to 4 of the drawings the numeral 10 designates a fragmentary portion of the fire-box of an ordinary kitchen stove or heater beneath 65 which is located the ash-box 11, and 12 indicates one of a series of juxtaposed fire or grate bars which are adapted for shaking to remove the ashes and cinders as hereafter explained, and said grate bars are journaled 70 in appropriate bearings 13. Beneath the aforesaid grate bars 12, and located in the ash box or pit 11, I mount a conveyer casting or trough 14 which is provided at its rear with a vertical wall 15 having a lip 16 75 adapted to seat snugly on a projecting rib or flange 17 formed integral with or attached to the back wall of the ash-box 11; and at the front end of the trough 14 there is formed a cylindrical extension 18 having 80 a surrounding flange 19 adapted to seat on the bottom 20 of the ash-box 11, and the upper portion whereof is forwardly inclined at 21, to fit snugly to the front thereof beneath the fire-bars 12 so that the ashes and 85 cinders at the front of the fire are projected into the conveyer trough 14. Obviously the flange 19 is of a width to fit snugly transversely across the ash-box 11. Longitudinally of the trough 14 and extension 18 90 there is journaled a hollow shaft 22, having a spiral conveyer portion 23 located in said trough 14, and, in order to provide an easy means for removing the conveyer 23, the shaft 22 is adapted to seat revolvably at 95 its rear end in a slotted bearing 24 formed in the end wall 15, flanges 25 being provided for preventing its accidental longitudinal displacement. At the front end the shaft 22, is journaled in the closed end 26, of 100 a cylindrical sleeve 27 adapted for longitudinal movement over the extension 18, and said sleeve 27 is provided with opposed longitudinal ribs or projections 28 for preventing said sleeve 27 from axial rotation having 105 a working fit in correspondingly shaped notched or cut out portions 29 formed for their reception in the ash-box door 30. It

- is also to be noted that the closed in end 26 of the sleeve 27 seats snugly in an opening 31, in the ash-box door 30, while at its rear end there are provided projections or ears 32, which prevent its withdrawal from engagement on the extension 18 as hereafter explained, also there is provided on its underside an opening 33 for the purpose hereafter set forth.
- 10 The hollow shaft 22, is formed at its forward end with an internally squared portion 34 to receive the elongated and correspondingly shaped end 35, of a shaker crank 36 provided with a handle 37, and it is to be here remarked that the forward ends of the fire bars 12 are correspondingly cored out at 38 so that the said shaker crank 36 serves the dual purposes of manipulating the conveyer 23 as well as for removing the ashes 15 and cinders from the firebox 10 by shaking the grate bars 12.

In the slightly modified form of the invention shown in Fig. 5, the device is shown as attached beneath the bottom of the ash box 11, and with the extension of the conveyer trough 14 projecting flush with the surface of the skirting flange 39, a pail or bucket 40 being also indicated for receiving the ashes and so forth when they are to be 20 removed from the ash-box and emptied or stored away.

The operation of my improved ash remover is briefly as follows. When the fire is to be shaken down the crank 36 is inserted in the cored out part 38 of the fire bar 12 and manipulated in the well known way, which results in the ashes falling into the conveyer trough 14. The cylindrical sleeve 27 is thereupon drawn out into extended position—as by a knob 41 Fig. 1—relative to the cylindrical extension 18 and the crank 36 inserted into operative connection with the hollow shaft 22, it being noted that the squared part 35 is long enough to 25 permit this connection when the parts 27—18 are thus extended. By rotating the crank 36 the spiral conveyer 23 will draw the ashes forward through the extension 18 into the extended sleeve 27 from whence they will 30 be discharged through the aperture 33 into the pail or receptacle 40. When the receptacle or pail 40 is full it can be removed for emptying after the sleeve 27 has been pushed into collapsed position relative to the extension 18.

From the foregoing description it will be readily understood that by my invention I provide an ash remover which can be readily built into any of the standard types of 35 stoves, heaters, ranges and furnaces at the time of manufacture and installation, or it may be made separate and inserted thereafter. Obviously when the device is built into new stoves, heaters, furnaces and ranges 60 the bottom of the ash box 11 may be inclined

downwardly from all sides to the trough 14 so that as the ashes are fed forward when the conveyer 23 is rotated the following ashes will all have a gravity feed or fall into the said trough 14; while at the same 70 time the inclined parts will prevent any clogging of the ashes in the extension 18.

Furthermore it will be obvious that by placing a cloth over the sleeve 27—when extended—and pail 40 all tendency of dust 75 to escape when the device is in use will be prevented, while the entire operation can be effected without opening the ash-box door 30.

Although I have described one practical embodiment of the invention it will be 80 readily understood that the various details of construction shown may be altered and changed to accommodate different service requirements without departing from the spirit and scope of the said invention and 85 as defined by the appended claims.

Having described my invention what I claim as new and desire to secure by Letters Patent is:—

1. An ash remover comprising a trough 90 having a cylindrical extension and a supporting flange, a spiral conveyer having a tubular shaft revolubly mounted in said trough, a cylindrical sleeve slidably mounted on the cylindrical extension and having a 95 closed in outer end and a discharge outlet on its lower part, said closed in end serving as a bearing for the front end of the conveyer shaft, and means for rotating the conveyer to expel the ashes from the trough 100 when the sleeve is in extended position.

2. An ash remover comprising a trough having a supporting and deflecting flange, a slotted wall at its inner end forming a bearing and a cylindrical extension at its front end, a cylindrical sleeve slidably mounted on the extension and having a closed in outer end, means for preventing the rotation of the sleeve about the extension, means for limiting the forward movement of the sleeve relative to the extension, a spiral conveyer, having a tubular shaft revolubly mounted in the trough and having flanges engaging the slotted wall and being also supported in the closed in outer end of the aforesaid sleeve, and means for rotating the conveyer to remove the ashes from the trough to the extension and into the sleeve when the latter is in extended position.

3. The combination with a grate and underlying ash box having an ash removing door, of an ash remover comprising a trough having a cylindrical extension and a supporting flange, a spiral conveyer having a tubular shaft revolubly mounted in said trough, a cylindrical sleeve slidably mounted on the cylindrical extension and having a closed in outer end and a discharge outlet on its lower part, said closed in end serving as a bearing for the front end of the con- 130

veyer shaft, and means for rotating the conveyer to expel the ashes from the trough when the sleeve is in extended position.

4. The combination with a grate and underlying ash box having an ash removing door, of an ash remover comprising a trough having a supporting and deflecting flange, a slotted wall at its inner end forming a bearing and a cylindrical extension at its front 10 end, a cylindrical sleeve slidably mounted on the extension and having a closed in outer end, means for preventing the rotation of the sleeve about the extension, means for limiting the forward movement of the sleeve 15 relative to the extension, a spiral conveyer having a tubular shaft revolvably mounted in the trough and having flanges engaging the slotted wall and being also supported in the closed in outer end of the aforesaid 20 sleeve, and means for rotating the conveyer

to remove the ashes from the trough to the extension and into the sleeve when the latter is in extended position.

5. The combination with a grate and ash box of an ash remover adapted for attachment thereunder and comprising a trough having a cylindrical extension and a supporting flange, a spiral conveyer having a tubular shaft revolvably mounted in said trough, a cylindrical sleeve slidably mounted 25 on the cylindrical extension and having a closed in outer end and a discharge outlet on its lower part, said closed in end serving as a bearing for the front end of the conveyer shaft, and means for rotating the conveyer to expel the ashes from the trough 30 when the sleeve is in extended position.

In testimony whereof I affix my signature.

RAYMOND T. HARTNETT.
